UNITED STATES PATENT OFFICE.

MARY K. MORSE, OF PHILADELPHIA, PENNSYLVANIA, EXECUTRIX OF HENRY G. MORSE, DECEASED, ASSIGNOR TO NEW YORK SHIPBUILDING COMPANY, OF CAMDEN, NEW JERSEY, A CORPORATION OF NEW JERSEY.

DRILLING-MACHINE.

No. 842,227.

Specification of Letters Patent.

Patented Jan. 29, 1907.

Application filed July 13, 1903. Serial No. 165,271.

To all whom it may concern:

Be it known that HENRY G. MORSE, deceased, late a citizen of the United States of America, residing in the city and county of Philadelphia, in the State of Pennsylvania, had invented certain new and useful Improvements in Drilling-Machines, of which the following is a true and exact description, reference being had to the accompanying drawings, which form a part thereof.

The invention relates to apparatus for drilling, countersinking, and the like, and has for its object to provide an apparatus of especial convenience and efficiency, and particularly one in which the pressure exerted on the tool during operation is automatically regulated.

The nature of the improvements will be best understood as described in connection with the drawings, in which he had illustrated the invention as embodied in a radial drilling or countersinking machine embodying a double-jointed jib-crane, which especial construction of its inner arm, whereby it is adapted to withstand torsional strains, as well as the ordinary strains coming upon crane-arms, forms the subject-matter of a copending application for Letters Patent, filed July 13, 1903, Serial No. 165,272.

In the drawings, Figure 1 is a side elevation of the crane and drilling apparatus supported thereon. Fig. 2 is a longitudinal section on the line 2 2 of Fig. 1 through the hoisting-cylinder supported on the outer arm

of the crane. Fig. 3 is a longitudinal section taken on the section line 3 3 of Fig. 1 of the feed-cylinder regulating the pressure exerted on the drilling or countersinking tool. Fig. 4 is a side elevation of the outer arm of the jib-crane and the parts supported thereon shown on a larger scale than Fig. 1 and showing the sleeve-post and bearings which support the outer crane-arm and the torsion member of the inner crane-arm in section.

Fig. 5 is a plan view of the outer crane-arm and parts supported thereon shown on the same scale as Fig. 4, with the immediately-connected parts of the inner crane-arm also depicted. Fig. 6 is a cross-section on the line 6 6 of Fig. 4; Fig. 7, a cross-section on

the line 7 7 of Fig. 4. Fig. 8 is a plan, on a large scale, showing the top of the pivot-post and connections shown in Fig. 1. Fig. 9 is a vertical section through the pivot-post of the inner crane-arm and the inner portions of 55 said arm, taken as on the section-line 9 9 of Fig. 8. Fig. 10 is a vertical section through the mechanism acting on and supporting the drill-spindle, taken as on the section-line 10 10 of Fig. 4. Fig. 11 is a section through the valve 60 mechanism controlling the hoisting-cylinder, taken as on the section-line 11 11 of Fig. 12. Fig. 12 is a view of the same valve mechanism, taken as on the section-line 12 12 of Fig. 11. Fig. 13 is a cross-section through the same 65 valve mechanism, taken as on the section-line 13 13 of Fig. 11. Fig. 14 is a section through the valve mechanism controlling the feed-cylinder, taken as on the section-line 14 14 of Fig. 15, Fig. 15 being a section on the line 15 70 15 of Fig. 14; Fig. 16, a cross-section on the line 16 16 of Fig. 15. Fig. 17 is a plan view, partly in section, of the valve regulating the admission, cut-off, &c., to the feed-cylinder and the valve-actuating rod and connec- 75 tions.

A indicates the base of the double-jointed jib-crane; A', a pivot-post supported on said base and in turn supporting the sleeve A², which, through the medium of a cap A³ and ball-bearings (indicated at a³) rests upon the top of the post a', having lateral roller-bearings A⁴ and A⁵, through which it rests against the sides of the pins.

A⁶ is a cylindrical extension, preferably of 85 practically the same diameter as the sleeve A², extending out from each side of said sleeve and forming a part of the compression and tension member of the truss forming the inner crane-arm. To this tubular extension 90 A⁶ is secured the tubular truss member B, having, as shown, at its outer end trunnion-like extensions B', to which are secured, as shown at B⁴, the rods B² B², forming the tension member of the truss, said arms continuing by a strap (indicated at B³) round the top of the sleeve A². 95

b² b² are turnbuckles for regulating the length of the rods B². Extending from the end of the tubular truss member B and 100

firmly secured thereto is the tubular extension C, which is firmly attached to and preferably formed integral with the sleeve-post C', having a cap C², which rests, preferably, through ball-bearings C³, as indicated in Fig. 4, upon the top of the sleeve-post C', and a downwardly-extending hub-like portion resting through roller-bearings upon the inside of the sleeve-post. Another cap C⁵, having, like the cap C², an inward tubular extension resting through roller-bearings upon the inside of the sleeve-post, is secured to the cap C² by means of a central rod, (indicated at C⁷.)

Firmly secured to the cap C², as shown in Figs. 4 and 6, are the angle-irons D D, forming what are ordinarily the tension members of the outer arm of the jib-crane, and also secured to the cap C² are the angle-irons E E, extending obliquely downward and secured at their outer ends to the angle-irons F F, which form what are normally the compression member of the truss and are secured at their inner ends to the cap C⁵, as shown in Fig. 7, and at their outer ends to the arm G, which in turn supports the bearings for the drill-spindle. This frame G has an upper bearing G', which indirectly supports and alines the upper end of the drill-spindle, and the lower bearing G², which directly alines said spindle. The upper end of the frame is, as shown, formed into a chamber G³, covered by a removable cover g³, and the bearing G' directly supports the prolonged hub G⁴ of a gear-wheel G⁵, which extends into the chamber G³. The hub G⁴ serves as a bearing for the spindle G⁶ and has secured to its splines (indicated at g⁴ g⁴) which enter grooves g⁶ g⁶ in the spindle, insuring that the spindle shall turn with the hub, while free to move vertically therein.

G⁷ indicates a grooved collar secured on the spindle G⁶ and supporting in its groove a collar G⁸, having trunnion-like extensions G¹⁰, to which are attached springs G¹¹ 11, connected at their upper ends, as shown, (see Fig. 10), with the frame G, the action of the springs being to normally draw the spindle G⁶ upward. Also supported through pivots on either side of the frame G are the arms H H, (see Figs. 4 and 5,) to the upper ends of which are pivotally connected the arms H' H', which at an intermediate part (see Fig. 10) are connected with the trunnion-pins G¹⁰ G¹⁰ and at their outer ends are secured to the arm H², which extends obliquely downward. Another arm H³ extends upward and obliquely downward from one of the arms H', connecting at its lower end with an arm H⁴, which is connected to the arm H², h² and h³, indicating the handles by which the operator can conveniently manipulate the action of the tool.

H⁵ is a downwardly-extending arm firmly

secured to the frame made up of the arms H', H², H³, and H⁴, preferably at the junction 65 of the arms H², H³, and H⁴.

I is the feed-cylinder secured to the end of the arms D D, preferably through trunnions, as indicated at i. A port I' enters the head of this cylinder, in which is situated (see Fig. 3) a piston I², having a piston-rod I³, which extends through the bottom of the cylinder and connects through a pin-bearing h' with the arms H' H' of the frame.

I⁴ indicates a flexible conduit leading from 75 the port I' to a valve-casing J³, said valve-casing being, as shown, connected through a cap-section J' with a block J, secured to the outer ends of the arms H' H'. The cap J' has formed in it the chamber J², which extends over a cylindrical valve-chamber J⁴, formed in the casing and having the ports indicated at J⁵, J⁶, and J⁷, the intermediate port J⁸ connecting with the conduit I⁴ and the upper and lower ports, respectively, with 80 the conduits indicated at L and L'. The valve-chamber has also formed in it the port indicated at J⁹, connecting the port J⁶ and chamber J².

K is a piston-valve moving in the cylindrical valve-chamber and having a portion 90 K', which also serves the purpose of the valve-stem and is connected to a fork K² and stud K³, (see Fig. 17,) with a tubular extension K⁴, having, as shown, a transverse pin K⁵ 95 extending through it and having at its end a collar, (indicated at K⁶.)

K⁷ indicates a rod forming another portion of the valve-actuating connection, said rod extending into the sleeve K⁴ and having a 100 slot K⁸, through which extends the pin K⁵. The rod K⁷ has a threaded extension K⁹, upon which screws an adjusting-nut K¹⁰, between which and the collar K⁶ of the sleeve K⁴ is situated a spring K¹¹. The function of 105 the spring is to normally keep the parts in the position shown in Fig. 17, while permitting the rod K⁷ to move inward to whatever distance is regulated by the length of the slot K⁸ or the distance between the end of 110 the rod K⁷ and the end of the stud K³. As shown, the end of the rod K⁷ is forked, as indicated at K¹², a pin K¹³ passing through the forks and supporting the bell-crank lever indicated at K¹⁴ K¹⁵, the arm K¹⁵ constituting 115 the grip of the lever, extending out so as to be within the operator's grasp at the same time as the handle h², (see Fig. 4,) a spring K¹⁶ normally forcing the grip-lever arm outward, as indicated in said figure.

L indicates a conduit for fluid under pressure, and L' an exhaust-conduit.

M is a motor secured on the inner end of the outer jib-crane arm and acting on a shaft M', which enters the chamber G³ and has secured to it the worm-wheel indicated at M², 125

said worm-wheel being in engagement with the worm gear-wheel indicated at G⁵.

N is a hoisting-cylinder supported on the outer jib-crane arm and in which (see Fig. 2) moves the piston N', having a piston-rod N², which extends through a stuffing-box in the front of the end of the cylinder and has connected with it the hoisting-chain indicated at N³, which in turn passes over the pulley-sheave indicated at N⁴. The cylinder N has a port N⁵ at its front end, into which screws, as shown, the valve-casing O', (see Figs. 11, 12, and 13,) said valve-casing having a chamber O², connecting through a valve O³ with the chamber O⁴, which chamber connects through the port O⁵ with the port N⁵ of the cylinder and through a valve-seated port O⁶ with the exhaust-conduit, O indicating a conduit for fluid under pressure which enters the chamber O², and O⁷ and O⁸ valves normally held by springs to the seats O⁹ and O¹⁰.

O⁹ is a spindle passing through the valve-casing and having attached to its inner end the lever-arms O¹⁰ and O¹¹, the arm O¹⁰ resting against an extension of the valve O⁷, and the arms O¹¹ against a shoulder formed on an extension of the valve O⁸.

O¹⁰ and O¹¹ are laterally-extending arms secured to the outer end of the spindle O⁹, and to which (see Fig. 1) are attached hand-chains O¹² and O¹³.

It will be understood that the inner crane-arm turns through the sleeve A², which forms a part of it, on the post A' and that the outer crane-arm turns through the caps C² and C⁵ upon the sleeve-post C', supported at the end of the inner arm, and it will also be obvious that the inner crane-arm in the construction illustrated is, by reason of having one of its truss member formed of a tube of considerable diameter, especially well adapted to resist torsional strains to which it is at times subjected, as well as to perform the ordinary functions of a crane in supporting weight.

The outer arm of the jib-crane is especially designed to resist the peculiar strains to which it is subjected by reason of the fact that it forms a part of a drilling or countersinking apparatus, having not only to support considerable weight, but also to resist at times an upward thrust due to the pressure of the drill upon the work below it. For this purpose and to preserve at all times the alinement of the tool the bracing-irons E E are of special value and importance, and they are also of importance in connection with a hoisting mechanism preferably supported on the crane-arm, as shown, and by means of which the work can be partially supported or transported.

With reference to the drilling apparatus

proper it will be understood that the spindle G⁸, supporting the drilling or countersinking tool G⁸ at its end, is actuated through the worm-gear G⁵ and the connections to the motor M and is normally held in elevated position by the action of the springs G¹¹. When it is desired to bring the tool into operation, the operator grasping the handles h² and h³ of the frame shifts the arms of the jib-crane so as to bring the tool into proper alinement with the work and presses the tool downward into contact with the work, the downward motion of the frame being communicated to the tool through its arms H' H': and the trunnion-pins G¹⁰ G¹⁰. The operator next draws inward the grip-lever K¹⁵, compressing the spring K¹⁶ and forcing the compound rod made up of the rods K⁷, sleeve K⁴, and fork K² outward, moving the valve K upward in the casing J⁸ so as to open the connection between the ports J⁵ and J⁶, permitting the pressure fluid to flow into the flexible conduit I⁴ and through it into the cylinder I, where, acting upon the piston and through the piston-rod I³, it communicates its pressure to the frame comprising the levers H' H' and through these levers to the drill-spindle and tool. The pressure admitted to the port J⁶ of the cylinder is communicated through the channel or port J⁸ to the chamber J² and acts upon the top of the valve K, and whenever this pressure reaches a determined amount, regulated by the adjustment of the spring K¹¹, the valve is moved downward in the casing to the intermediate position shown in Figs. 14 and 15, cutting off the supply of pressure fluid to the cylinder, which therefore is only able to exert upon the tool the pressure predetermined by the adjustments of the spring K¹¹, the downward movement of the valve being accomplished by the compression of this spring and the incidental sliding of the sleeve K⁴ on the end of the rod K⁷ until port J⁵ is closed, thus cutting off further admission of fluid until the pressure in cylinder I and chamber J² permits the spring to again open the valve. As soon as the drilling or countersinking is completed the operator releases the grip-lever K¹⁵, whereupon the spring K¹⁶ forces said grip-lever outward, withdrawing the compound valve-actuating rod and drawing the valve to the position in which it connects the ports J⁶ and J⁷, thus connecting the feed-cylinder with the exhaust and permitting the springs G¹¹ to draw up the tool and spindle to normal non-operative position.

The operation of the valves illustrated in Figs. 11, 12, and 13 in connection with the hoisting-cylinder needs but little explanation. Normally both of the valves O⁷ and O⁸ are closed. When it is desired to admit pressure fluid to the cylinder and draw up the hoisting-chain, the spindle O⁹ is turned in the

direction to raise the arm O^{10} , which in turn raises the valve O^7 , permitting the pressure fluid to pass through the port O^3 into the chamber O^4 and thence through the port O^5 to the cylinder. Whenever the hoisting-chain is released, the valve will automatically close cutting off further supplies to the hoisting-cylinder, and whenever it is desired to release the fluid in the cylinder the spindle O^9 is turned in the direction to raise the arm O^{11} , which lifts the valve O^8 from its seat, permitting the fluid in the cylinder to exhaust through the chamber O^4 and port O^6 .

Having now described the said invention, what he claims as new, and desires to secure by Letters Patent, is—

1. In a drilling-machine, the combination with a drill-actuating spindle, means for rotating the same and connections by means of which the drill-spindle is moved longitudinally, of a feed-cylinder having a piston and rod connected to the mechanism for moving the spindle longitudinally, a conduit for fluid under pressure leading to said feed-cylinder, a valve-casing situated in said conduit, having ports leading to the supply and delivery sections of the conduit and to exhaust, a valve working in said casing, means whereby said valve is normally held in the position connecting the cylinder with the exhaust, a yielding connection whereby the valve is moved to connect the cylinder with the supply of pressure fluid and means whereby the valve is moved to cut off the supply from the cylinder actuated by the pressure in the cylinder.

2. In a drilling-machine, the combination with a drill-actuating spindle, means for rotating the same and connections by means of which the drill-spindle is moved longitudinally, of a feed-cylinder having a piston and rod connected to the mechanism for moving the spindle longitudinally, a conduit for fluid under pressure leading to said feed-cylinder, a valve-casing situated in said conduit, having a cylindrical chamber J^4 with ports opening into the sides thereof from the supply and delivery conduits and from the exhaust, said valve-casing having also a chamber J^2 extending over the end of the chamber J^4 and in permanent connection with the feed-cylinder, a piston-valve working in the cylindrical chamber J^4 having its head exposed to the pressure in chamber J^2 means whereby said valve is normally held in the position connecting the feed-cylinder with the exhaust, and a yielding connection whereby said valve is shifted to connect the feed-cylinder with the supply and which connection permits the valve to move automatically to position to close the supply when the pressure in chamber J^2 attains a determined amount.

3. In a drilling-machine, the combination with a drill-actuating spindle, means for rotating the same and connections by means of which the drill-spindle is moved longitudinally, of a feed-cylinder having a piston and rod connected to the mechanism for moving the spindle longitudinally, a valve-casing connected to and moving with the spindle said casing having a cylindrical valve-chamber provided with lateral ports one connecting with a pressure-fluid supply, one with an exhaust and the third with the feed-cylinder through a flexible conduit, and said casing having also a chamber situated over one end of the valve-chamber and in permanent connection with the port leading to the feed-cylinder, a piston-valve moving in the valve-chamber, a valve-actuating connection having the capacity to yield for a definite distance under determined pressure said connection also moving with the spindle and acting normally to hold the valve in position to connect the feed-cylinder and exhaust-port.

4. In a drilling-machine, the combination with a guiding-head, a drill-actuating spindle and means supported on said head for rotating and means for elastically supporting the spindle, of a feed-cylinder for moving the spindle downward, a pressure-conduit leading to the feed-cylinder, a valve-casing situated in said conduit having in addition to the ports connecting it in the conduit, an exhaust-port, a valve moving in said casing to connect the feed-cylinder with the supply or exhaust and automatic means actuated by the pressure in the feed-cylinder acting to cut off the supply to said cylinder.

5. In a drilling-machine, a support having a capacity of universal movement in a horizontal plane, having in combination a drill-spindle supported thereon in suitable guides, a motor for rotating said spindle also supported thereon and suitably connected to the spindle, a feed-cylinder and piston connected to move the spindle longitudinally, a guiding-frame connected to actuate the supporting device and connected also to the spindle and piston and adapted to move in all directions with the spindle and the piston of the feed-cylinder, a valve-casing secured to and moving with said frame having ports connecting with a flexible conduit for fluid under pressure, with the feed-cylinder and with an exhaust, a valve working in said casing and a valve-actuating rod connected to the guiding-frame and having a fixed relation to the frame.

6. In a drilling-machine, a support having a capacity of universal movement in a horizontal plane, having in combination a drill-spindle supported thereon in suitable guides, a motor for rotating said spindle also supported thereon and suitably connected to the

spindle, a feed-cylinder also supported on the movable support and having a piston connected to move the spindle longitudinally, a guiding-frame connected to actuate the movable support and connected to the spindle and piston of the feed-cylinder and moving in all directions with the spindle, a valve-casing and valve-actuating rod connected to the guiding-frame, said casing having admission, delivery and exhaust ports, a conduit

for fluid under pressure connecting through the casing with the feed-cylinder, and a valve working in the casing and actuated by the rod aforesaid.
